(57) **CLAIM**

The ornamental design for a label applicator as shown and described.

DESCRIPTION

FIG. 1 is a perspective view showing my label applicator as seen from the top, front, and first side;

FIG. 2 is a front elevation view thereof;

FIG. 3 is a second side elevation view thereof;

FIG. 4 is a rear elevation view thereof;

FIG. 5 is a first side elevation view thereof;

FIG. 6 is a top plan view thereof; and,

FIG. 7 is a bottom plan view thereof.

The broken lines shown in the drawings represent unclaimed subject matter and form no part of the claimed design.

1 Claim, 5 Drawing Sheets
